UNITED STATES PATENT OFFICE.

BURR D. VIERS, OF RED LODGE, MONTANA

ELECTRICALLY-OPERATED SAW.

1,425,152.

Specification of Letters Patent. Patented Aug. 8, 1922.

Application filed February 23, 1921. Serial No. 447,004.

To all whom it may concern:

Be it known that I, BURR D. VIERS, a citizen of the United States, residing at Red Lodge, in the county of Carbon, State of Montana, have invented certain new and useful Improvements in Electrically-Operated Saws; and I do hereby declare the following to be a full, clear, and exact description of the invention, such as will enable others skilled in the art to which it appertains to make and use the same.

This invention relates to new and useful improvements in saws and particularly to hand saws.

15 One object of the invention is to provide a hand saw which is electrically driven, and which can be easily and quickly adjusted to rotate in either direction.

Another object is to provide an electrically driven saw which is provided with a novel form of gage by means of which a piece may be sawed from a board without the use of a square or mark on the board as a guide.

25 Another object is to provide an electrically operated saw which has means for preventing the saw from dropping into the kerf and hanging or sticking.

Other objects and advantages will be apparent from the following description when taken in connection with the accompanying drawing.

In the drawing:

Figure 1 is a side elevation of a saw made 35 in accordance with the invention.

Figure 2 is a top plan view of the same.

Figure 3 is a side elevation viewed from the opposite side from that of Figure 1, to show the arrangement of the gage.

40 Figure 4 is a sectional detail of the handle of the saw, showing the circuit closer.

Figure 5 is an enlarged vertical sectional view, through the saw shaft, to show the removable collar for holding one or the 45 other of the smaller gears in mesh with the larger gear.

Referring particularly to the accompanying drawing 10 represents a casing in which is mounted the electric motor, the shaft of 50 said motor extending forwardly from the front end of the casing, through a bearing 11. The motor shaft is represented by the numeral 12. Encasing the shaft 12 is a tube 13, which extends to and is connected 55 with an angular housing 14, said shaft 12 extending into the housing where it is pro-

vided with a bevel gear 15. On the tube 13, between the motor casing and the housing, is formed a hand grip 16, and a disk shield 17, which is adapted to be grasped by one 60 hand of the user. On the rear end of the motor casing, and extending downwardly and rearwardly therefrom, is a pistol grip 18 through which pass the wires 19 to the motor, the other ends of the wire being 65 provided with the usual screw plug for engagement in the socket of an ordinary electric light fixture. One of the wires is separated within the grip 18, and the ends connected to two adjacent contact members 21 70 and 22 for engagement by the spring member 23, carried by the inner end of the sliding plunger 24. This plunger is disposed through the forward side of the pistol grip 18, and has a finger piece 18' on its outer 75 or forward end which is arranged to be engaged by the finger of the user so that upon pressing said plunger inwardly the member 23 will contact with the members 21 and 22, to complete the circuit and start the 80 motor. A coil spring is disposed around the plunger 24 between the wall of the grip 18, and a vertical guide 25, within the grip, said spring normally holding the plunger 85 yieldably out of circuit closing position.

Extending transversely through the housing 14 is a shaft 26, and having one end bifurcated, as shown at 26', for engagement in two openings in the circular saw blade 27, nuts 28 being engaged on the 90 bifurcations to retain the saw in position. The shaft 26 is supported in suitable bearings 29, carried by the housing. On the shaft 26 is splined a sleeve 30', on the ends of which are secured two smaller bevel gears 30 and 31, so spaced apart that only one at a time may be meshed with the larger gear 15 when the sleeve is moved longitudinally on the shaft. To maintain either of the gears in mesh with the large gear a split collar 32 is engaged around the shaft 26, between either gear 30 or 31, and the adjacent side wall of the housing. Thus the large gear 15 will drive the shaft 26 in either direction to rotate the saw in the 100 direction desired by the user.

Carried by the lower portion of the housing 14, and extending from the side opposite to that of the saw, is a graduated bar 32', said bar being preferably flat on the upper side and rounded on the lower side, and on the said upper flat face are formed inch and

fractional inch graduations. A member or bar 33, having the enlargements 34 and 35 at its opposite ends is arranged to be slidably adjusted on the said bar 32'. The enlargement 35 is formed with an approximately triangular opening 35' therethrough for the reception of the bar 32', a screw 36 being disposed through the upper side of the enlargement for engagement in the upper 10 face of the bar to maintain the member 33 in different adjusted positions along the bar. Rotatably carried by the lower portion of each of the enlargements 34 and 35, is a vertically disposed roller 37 which rollers are 15 adapted to bear against the side or end edge of a board to be cut, while the saw is making its cut, said rollers serving to maintain the saw in proper position so that it will cut on a straight line parallel with the edge 20 or end of the board, without the necessity of using a square, or making a mark on the board.

Carried by the lower side of one side wall of the housing 14 is a roller 38 which is 25 adapted to roll on the face of the board to hold the saw against going too deep into the kerf, when starting the sawing, and while proceeding along the board.

In the operation of the saw, the operator 30 first adjusts the gage 33 along the bar 32' to the graduation on said bar representing the distance from the end or side edge of the board the saw is to cut. The operator then grasps the pistol grip in the hand, and after 35 placing the cutting edge of the saw against the board, presses the plunger 24 inwardly to close the circuit, when the motor will drive the saw. The device is then moved forwardly, with the rollers 37 against the

side or end edge of the board, and the roller 40 38 on the upper face of the board, until the saw has cut therethrough, throughout the length or width of the board, as the case may be.

The plunger 24 is normally held out of 45 circuit closing position by the coil spring thereof, thus requiring the operator to hold the plunger inwardly while the saw is in operation, and permitting the plunger to automatically move out of circuit closing position when pressure thereon is relieved.

By means of the removable spacing collar 32, either of the gears 30 or 31 may be maintained in mesh with the gear 15, so that the saw may rotate in the direction desired by 55 the operator.

What is claimed is:

In an electrically operated saw, a pistol frame supporting a motor and a drive shaft driven by the motor, a frame on the outer 60 end of the pistol frame, a transverse shaft mounted in the last-named frame and carrying a saw on one end thereof, a transverse bar carried by the same frame and projecting from one side of the frame, an angularly extending arm mounted for longitudinal 65 slideable adjustment on the bar and carrying rollers rotatable on vertical axes, rollers rotatable on horizontal axes on the said last-named frame, and means for controlling the circuit to the motor.

In testimony whereof, I affix my signature, in the presence of two witnesses.

BURR D. VIERS.

Witnesses:

HARRY VIERS,
ETHEL DOUGLASS.
